UNITED STATES PATENT OFFICE.

GOODRICH Q. LEWIS, OF WHEATON, ILLINOIS, ASSIGNOR TO WILLIAM H. MINER, OF CHAZY, NEW YORK.

TANDEM DRAFT-RIGGING.

1,340,490.

Specification of Letters Patent.

Patented May 18, 1920.

Application filed January 31, 1916, Serial No. 75,309. Renewed May 9, 1918. Serial No. 233,608.

To all whom it may concern:

Be it known that I, GOODRICH Q. LEWIS, a citizen of the United States, residing at Wheaton, in the county of Du Page and 5 State of Illinois, have invented a certain new and useful Improvement in Tandem Draft-Riggings, of which the following is a full, clear, concise, and exact description, reference being had to the accompanying 10 drawings, forming a part of this specification.

This invention relates to improvements in tandem draft riggings, and more particularly to the side castings employed therein.

15 Objects of the invention are to provide a side casting for tandem draft riggings having great strength, long life, so designed that it will be free from casting and annealing strains, relatively easy and cheap to 20 manufacture, and wherein the web and other parts of the casting are of substantially uniform thickness.

Another and more specific object of the 25 invention is to provide novel means for supporting a follower carrying strap by means of short bolts which are readily removable.

The invention furthermore consists in the 30 improvements in the parts and devices and in the novel combination of the parts and devices herein shown, described or claimed.

In the drawing forming a part of this specification, Figure 1 is a longitudinal, central, vertical, sectional view of a car showing my improvement in connection therewith, the parts of the gear being indicated by dotted lines. Fig. 2 is a longitudinal, horizontal, sectional view of the structure illustrated in Fig. 1 and taken substantially on the line 2—2 thereof. Fig. 3 is a vertical, 40 transverse sectional view taken substantially on the line 3—3 of Fig. 1. Figs. 4 and 5 are side elevation and top plan views, respectively, of one of the side castings. And Figs. 6 and 7 are detail, vertical, sectional views of the casting taken substantially on the lines 6—6 and 7—7, respectively, of Fig. 4.

In said drawing, 10—10 denote channel center sills of a car underframe arranged 50 in the usual manner, the latter having secured thereto and on their inner faces Z shaped plates 11—11, the latter being substantially deeper than the sills and having their upper flanges extended inwardly and 55 their lower flanges extended outwardly, said

plates 11—11 extending from the body bolster 12 to the end sill 13 and abutting the latter with the transverse flanges 14—14. Said plates 11—11 are shown as connected at the top by a transversely extending horizontal plate 15.

Secured to the inner face of each of the plates 11—11 is a tandem side casting which I have designated generally by the reference A, the latter having the usual number of 60 main stops and also limiting stops as hereinafter more specifically described. Co- 65 operable with the side castings A—A are the usual members of a tandem draft gear comprising front and rear followers 16—16 and intermediate followers 17—17; tandem arranged springs 18—18; yoke strap 19 having a center post or thimble 20, all four faces of which are preferably rounded; and 70 draw-bar 21.

Each casting A is provided with a main front follower stop 22, a rear main follower stop 23 and front and rear intermediate follower stops 24 and 25. Intermediate each set of main follower stops each 80 casting A is provided with a limiting stop 26, each of the latter, of course, having a front and a rear shoulder to limit the movement of the respective followers and prevent setting or over-compression of the 85 springs.

As clearly appears from the horizontal cross section in Fig. 2, the respective front, rear, and center or intermediate main follower stops and also the limiting stops are 90 formed by vertically extending or upright bends or convolutions in the web of the casting. The casting also has provided in the web thereof, and located between each main follower stop or shoulder and adjacent limiting stop shoulder, horizontal bends or convolutions 28—28 which extend between the stops but not across the same. Those horizontal convolutions or bends which appear as depressions when looking at the inner 100 face of the casting, provide seats for rivets 29—29 by which the casting is secured to the Z plates 11—11. At its front end, each of the castings A is provided with an inwardly 105 extending transverse flange 30 which is adapted to abut the end sill.

At the center or intermediate post of each casting, the inner face thereof, which is formed by the web of the casting, has portions thereof cut away as indicated by the 110

substantially rectangular openings 31-31. Extending between the shoulders or stops 24-25 of the center post of the casting are horizontal strengthening and bracing ribs 5 32-32 and a lower flange 33. As clearly appears from Figs. 4 and 5, the cutaway portions of the inner face of the center post of the casting are so located as to leave wide bearing and wearing faces 34 along the inner edges of the ribs 32 and also along the inner edges of the top and bottom flanges of the casting at that point, as indicated at 10 35-35.

By referring to Fig. 2, it will be seen that 15 the web of the casting at the main front and rear follower stops or shoulders is extended, in each instance, a short distance toward the adjacent end of the casting as indicated at 36 and 37, whereby comparatively wide, 20 vertically extending, bearing and wearing faces are provided at these points also. For strength, each casting is provided with horizontally extending ribs 38-38 between the front shoulder 22 and end flange 30, and 25 ribs 39-39 from the rear shoulder 23 to the rear end of the casting. Short intermediate horizontal strengthening ribs 40-40 may also be provided for the rear stop shoulder, as clearly indicated in Figs. 4 and 7.

30 In order to support the followers and properly guide the same, follower carrying straps 41-41 are provided, the latter being secured at their ends by means of short bolts 42-42 which are mounted in transversely 35 extending, substantially T shaped slots 43-43 formed at the bottoms of the front and rear stop shoulders 22 and 23.

At the center of the casting, where it is 40 always necessary to support the follower strap, the bottom flange 33 of the casting is provided with a perforation 44 adapted to receive the short center bolt 45. In order to be able to insert and remove the bolt 45, the lower horizontal rib 34 is provided with an 45 elongated slot 46 located above the perforation 44 so that the bolt 45 may be inserted through the lowermost rectangular opening 31 in a horizontal position, then tilted to a vertical position with the head passing 50 through the slot 46 and then dropped vertically into the perforation 44. By this arrangement, the strength of the casting at the center post is maintained, particularly 55 at the bottom thereof since there is no cut or opening in the inner face and also the lower wearing and bearing surface on the inner face of the center post is maintained. At the same time, I am enabled to use a short bolt and to readily insert and remove 60 the same whenever desired. It will also be noted that on account of the center bolt being mounted in a perforation, the follower carrying strap cannot work off laterally accidentally even should the ends become loose.

65 At the top thereof, each casting A is pro-

vided with a combined follower guiding and strengthening flange 47 which extends over and closes the tops of all the main and limiting stops. And in this connection, it will be noted that said flange 47 decreases 70 in width from the center of the casting toward each end thereof, the contour of the edge of said flange 47 being either a straight taper or somewhat broken as indicated in Fig. 5. It will be noted that the depth of 75 the center post of the casting is considerably more than the depth of the end stops or shoulders so that the center post or stop of the casting serves as a pivot or fulcrum for the thimble of the yoke to swing about 80 and the tapering upper guide flange 47 serves a similar function for the upper arm of the yoke strap. By retaining the inner wearing and bearing face of the center post of the casting for the thimble to rock on 85 and by providing an elongated tapering surface for the yoke arm to bear against, the life of the casting and also of the yoke and gear is lengthened.

By referring to Figs. 3 and 4, it will be 90 seen that the inner faces of the limiting stops 26 are curved as indicated at 48 to more nearly conform to the shape of the springs and to maintain the latter in proper position. Each casting is also provided 95 with horizontal strengthening ribs 49 and 50 on the rear face thereof, as indicated in Fig. 4. To prevent spreading of the sills 10 and Z plates 11, transversely extending tie plates 51 and 52 are provided, the latter 100 being detachably connected to the lower flanges of the plates 11-11 as by bolts 53 and U shaped clips 54.

From the preceding description, it will be seen that the casting which I have provided has all the parts thereof of substantially the same thickness throughout, thereby minimizing casting strains and annealing strains when the castings are rendered malleable. By forming the stops by means of 110 vertical convolutions in the web of the casting, great strength is obtained and at the same time large bearing surfaces are provided on the inner side of the casting. The horizontal convolutions also add to the 115 strength of the casting against transverse bending or buckling strains.

I claim:

1. A tandem gear side casting having front, rear, and center main stops, each having inner bearing surfaces, the front and rear stops being provided with open slots at their lower ends to receive short bolts for supporting the ends of a follower carrying strap, the center stop having the lower flange 120 perforated to receive a bolt therethrough and a horizontal rib spaced above said flange, said rib being provided with an elongated slot and the inner face of said center stop having an opening between said lower flange 130

and said rib, whereby a short bolt may be inserted through said opening, then tilted with its head through said slot in the rib and finally dropped vertically down into said 5 perforation in the lower flange.

2. A side casting for draft riggings having a hollow stop with a flange at the bottom thereof, said flange being perforated to receive a bolt, said stop having also a horizontal 10 rib spaced above said flange and within the stop, said rib being slotted, the inner face of said stop being provided with an opening located between said lower flange and

horizontal rib, whereby a short bolt may be inserted horizontally through said opening, 15 then tilted vertically with its head through the slot in said rib, and finally dropped vertically into the perforation in the lower flange.

In witness that I claim the foregoing I 20 have hereunto subscribed my name this 17th day of Jan., 1916.

GOODRICH Q. LEWIS.

Witness:

ELIZABETH M. BRITT.
